UNITED STATES PATENT OFFICE.

FRANCISCO RIVIERE AND FERNANDO RIVIERE, OF BARCELONA, SPAIN.

APPARATUS FOR THE MANUFACTURE OF WIRE-NETTING.

1,401,557.

Specification of Letters Patent. Patented Dec. 27, 1921.

Application filed July 17, 1918. Serial No. 245,337.

(GRANTED UNDER THE PROVISIONS OF THE ACT OF MARCH 3, 1921, 41 STAT. L., 1313.)

To all whom it may concern:

Be it known that we, FRANCISCO RIVIERE and FERNANDO RIVIERE, both subjects of the King of Spain, residing at Ronda de San Pedro, Barcelona, in Spain, have invented certain Improvements in Apparatus for the Manufacture of Wire-Netting, (for which we have filed applications in Spain, March 3, 1917, No. 64,053; France, March 2, 1918, No. 10 20,729; Great Britain, March 4, 1918, No. 113,968, and in Germany, March 4, 1918, No. 73,843,) of which the following is a specification.

This invention is an improvement in the apparatus described and claimed by us in our co-pending application for Letters Patent, Serial No. 103861, filed 15th June, 1916, and the said improvement consists in adapting the apparatus to the manufacture of netting of the type wherein reinforcing wires are introduced into the fabric, in a manner which will be made clear in the following description of the invention.

The invention is illustrated in the accompanying drawings, in which—

Figure 1 represents a sample of netting made with the improved apparatus, and

Fig. 2 shows a portion of the receiving drum of the machine, with finished fabric thereon.

Fig. 3 is a vertical section of part of the apparatus, including the receiving drum, and

Fig. 4 is a plan view thereof, with the drum removed.

Figs. 5 and 6 are side views, from different angles, of one of the net engaging pins on the receiving drum, drawn to a larger scale than Figs. 3 and 4.

As best shown in Fig. 1, the hexagonal meshes of the fabric are formed by wires 24 and 25, twisted together at the junctions or sides of the meshes, the twist being in opposite directions above and below the comparatively straight parts 26 of the wire. In addition to the wires 24 and 25 there are reinforcing wires 27, extending through the fabric and vertically intersecting each mesh in their course, these wires 27 being twisted together with the wires 24 and 25 as shown.

The apparatus described in our prior specification cited produces fabric composed solely of wires such as the wires 24 and 25, which may be designated mesh forming

wires, and in our present invention we use, 55 for the disposal of these wires, appliances similar to those set forth in the said prior specification, these appliances being, however, combined with means for introducing the reinforcing wires 27. 60

The mesh forming wires pass through guides 1 and 2 (Figs. 3 and 4) reciprocable in a channel in a bed 3. Upon the said bed is a carrier 4, carrying a series of rotatable twisting wheels, three of which are shown 65 in Fig. 4, designated 20, 21 and 22. These wheels have teeth 33 engaged with a rack 5 slidable in the carrier, and each wheel has an axial bore 18, flared in opposite directions from a narrow central part or throat, 70 a radial slot giving access to this bore from one side of the wheel, as best shown in Fig. 4. The mesh forming wires, of which Fig. 4 shows three pairs designated 10—11, 12—13, 14—15 pass through holes 6 and 7 75 in the guides 1 and 2 respectively.

All these elements of the apparatus are found in our prior specification, and the manner of their operation, to be described hereinafter, is the same as in that specification. The intermittently rotating receiving drum 34, however, differs from that shown in our prior specification, in that the pins thereon for engaging the netting are split, each pin having two jaws 37, 38 (Fig. 5) 80 85 diverging to form a V-shaped gap adapted to receive one of the reinforcing wires when the pin engages the top of a mesh, as shown in Fig. 2.

The reinforcing wires, of which Fig. 4 90 shows three, designated 29, 30, and 31, pass upward through the machine, like the mesh forming wires, but instead of passing through the guides 1 and 2, they pass between these two guides, so that the movement of the latter does not affect them. With the parts in the position shown in Figs. 3 and 4, each twisting wheel has passing through its bore one pair of mesh forming wires and one reinforcing wire, the reinforcing wire lying between the mesh forming wires. The first step, from this position, is the movement of the rack 5, say, in the direction of the arrow C; by this means the twisting wheels are rotated, and each wheel twists together the wires which it engages, producing a twist such as shown in Fig. 1. The drum 34 then rotates, as 95 100 105

indicated by the arrow F, and the carrier 4, with the twisting wheels, recedes from the wires, as indicated by the arrow D, whereupon the wire guides 1 and 2 are moved in opposite directions, as indicated by the arrows A and B, to bend apart the mesh forming wires and re-group them with the reinforcing wires, which remain stationary. The carrier 4, which has meanwhile been traversed laterally in the direction of the arrow E, through a distance equal to half the width of a mesh, then advances toward the wires, so that the twisting wheels re-engage the wires, whereupon the rack 5 is again actuated, and the wires receive another twist, and so on.

In the following cycle of operations the parts 1, 2, and 4 move, of course, in the directions opposite to those indicated by the respective arrows.

Instead of moving both the wire guides, one of them may remain stationary, the travel of the other being doubled, producing a trapezoidal mesh.

It will be understood that it is not essential to have a reinforcing wire for each longitudinal series of meshes. These wires may, for example, be restricted to alternate series of meshes, or used in any other selected order. The said wires may also be of different thickness to the mesh forming wires, and may be composite, in the form of cables or the like.

Claims—

1. In a wire net machine two parallel wire guides, each arranged to guide a row of spaced apart mesh forming wires, means for guiding through the machine a series of reinforcing wires parallel with the mesh forming wires prior to the formation of the mesh, a plurality of twisting wheels having axial bores and slots giving lateral access to said bores, for engaging the wires, a carrier for said wheels, reciprocable into and from co-operative position with said mesh forming wires and said reinforcing wires, and also reciprocable laterally of said rows of wires, and means for rotating said wheels in both the positions to which they are movable by the lateral reciprocation of said carrier.

2. In a wire net machine two parallel wire guides, each arranged to guide a row of spaced apart mesh forming wires, means for guiding through the machine a series of reinforcing wires parallel with the mesh forming wires prior to the formation of the mesh, a plurality of twisting wheels having axial bores and slots giving lateral access to said bores, for engaging the wires, a carrier

for said wheels, reciprocable into and from co-operative position with said mesh forming wires and said reinforcing wires, and also reciprocable laterally of said rows of wires, and means for rotating said wheel in both the positions to which they are movable by the lateral reciprocation of said carrier, said wheel rotating means including teeth on said wheels and a rack engaged with said teeth.

3. In a wire net machine two parallel wire guides, each arranged to guide a row of spaced apart mesh forming wires, a net receiving drum above said guides, net engaging members upon said drum, each of said members having two divergent jaws adapted to engage and guide a reinforcing wire extending upward from between said parallel wire guides, a plurality of twisting wheels having axial bores and slots giving lateral access to said bores for engaging the wires, a carrier for said wheels, reciprocable into and from co-operative position with said mesh forming wires and said reinforcing wires, and also reciprocable laterally of said rows of wires, and means for rotating said wheels in both the positions to which they are movable by the lateral reciprocation of said carrier.

4. In a wire net machine two parallel wire guides, each arranged to guide a row of spaced apart mesh forming wires, said guides being oppositely reciprocable one half the width of a mesh, an intermittently rotating net receiving drum above said guides, split net engaging pins upon said drum, each having a V-shaped mouth adapted to engage and guide a reinforcing wire ascending to said drum from between said parallel guides, a plurality of twisting wheels, each having an axial bore and a slot giving lateral access to said bore, a carrier for said wheels reciprocable to move said wheels into and out of engagement with said mesh forming wires and said reinforcing wires, and also reciprocable laterally of said rows of wires one half the width of a mesh, and means including a rack and teeth on said wheels, for rotating the latter in both the positions to which they are moved by the lateral reciprocation of said carrier.

In witness whereof we have signed this specification in the presence of two witnesses.

FRANCISCO RIVIERE.
FERNANDO RIVIERE.
